UNITED STATES PATENT OFFICE

SAM E. LIVINGSTON, OF BLOOMINGTON, ILLINOIS

DESIGN FOR A COMBINATION HANGER

Application filed October 25, 1930. Serial No. 37,378. Term of patent 7 years.

To all whom it may concern:

Be it known that I, SAM E. LIVINGSTON, a citizen of the United States, residing at Bloomington, in the county of McLean and State of Illinois, have invented a new, original, and ornamental Design for a Combination Hanger, of which the following is a specification, reference being had to the accompanying drawing, forming part thereof. The figure is a perspective view of the combination hanger embodying my design.

I claim:

The ornamental design for a combination hanger substantially as shown.

SAM E. LIVINGSTON.
